John Petrosky Inventor

By Clarence O'Brien
Attorney

UNITED STATES PATENT OFFICE

JOHN PETROSKY, OF NILES, OHIO

TOY

Application filed October 17, 1930. Serial No. 489,461.

This invention relates to toys and an object of the invention is to provide a spinning toy that is very attractive to the children that may be operated continuously by merely pulling on a cord.

A further object of the invention is to provide a toy that is strong, compact and durable, thoroughly reliable for entertaining children, very simple in its operation, productive of much amusement and comparatively inexpensive to manufacture and assemble.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claims hereto appended.

In the drawings wherein like reference characters denote corresponding parts throughout the several views:—

Figure 1 is a side elevation of the toy in accordance with the present invention.

Fig. 2 is a detailed vertical section therethrough, and

Fig. 3 is a bottom plan view thereof.

In the drawings wherein for the purpose of illustration is shown the preferred embodiment of my invention, 4 indicates an oval shell adapted to be held in the left hand while the toy is being operated.

The shell 4 in the operating position is disposed so that the major axis thereof will be vertical. The shell is mounted on the upper portion of the drive shaft 6 which extends through the restricted openings 7, 8, in the

upper and lower ends of the shell respectively. These openings communicate with the hollow interior 5 of the shell. On the upper end of the drive shaft 6 is a round head 9 that bears against the upper end of the shell. The

openings 7, 8 form bearings for the drive shaft 6. The free projecting end 10 of the drive shaft has mounted thereon the spinning head 11 that rotates with the shaft. Anchored to the lower end of the spinning head

11 are radially projecting blades 12, spaced at

quadrant about the head. The blades are notched at their centers so that the notched part of one blade will engage the notched part of the other blade as shown in Fig. 2 and the blades passed through slots formed in the lower end of the head and are frictionally held therein or the blades could be held in the slots in any other suitable manner. Extending through the side wall of the shell 4 is an opening 13 preferably formed on the minor axis of the shell. The drive shaft 6 extends through the major axis of the shell and therefore the opening 13 will be disposed at right angles to the drive shaft and in communication with the interior of the shell.

Wound about an intermediate portion of the drive shaft 6 as at 14 is the inner end of the drive cord 15, on the free outer end of which is the pulling ring 16.

In the operation of the toy the cord 15 is extended from the shell, the spinning head 11 is turned until the cord is wound on the drive shaft 6, within the interior 5. The cord 15 is then pulled outwardly by means of the ring 16. When the cord 15 is pulled outwardly, the head 11 will spin and cause much amusement to the children. At the end of the stroke the cord 15 is held loose whereupon the cord will wind inwardly on the shaft in preparation to being pulled again. It therefore follows that the head 11 may be continuously spun by intermittent pulls on the cord. When the head is rotated the blades 12 act to set up a whirling noise or buzzing sound and said blades also act to set up an air current so that the device simulates the action of a propeller thus making the device more attractive to children.

The present embodiment of the invention has been disclosed in considerable detail merely for the purpose of exemplification, since in actual practice it attains the features of advantage enumerated as desirable in the statement of the invention and the above description.

It is to be understood that by describing in detail herein any particular form, structure, or arrangement, it is not intended to limit the invention beyond the terms of the claim or the requirements of the prior art.

Having thus described my invention, what I claim as new is:—

A toy comprising a shell of substantially elliptical shape having a bearing opening at each end and also an opening in the side thereof, a shaft having one end journalled in one bearing opening, and an intermediate portion of said shaft journalled in the other bearing opening, the lower end of the shaft projecting below the shell, a head anchored to the projecting end of the shaft and abutting the shell, a cord having one end anchored to the shaft interiorly of the shell, said cord being trained through the opening in the side of the shell, the outer end of the head having radial slots therein, blades passing through the slots and projecting from the head, said blades being set edgewise to the axis of the device, and a pull ring on the free end of the cord.

In testimony whereof I affix my signature.

JOHN PETROSKY.
